CUT PILE CARPETING AND METHOD OF MAKING THE SAME

Leslie L. Walmsley, Swarthmore, Pa., assignor to American Viscose Corporation, Philadelphia, Pa., a corporation of Delaware

Filed Dec. 30, 1957, Ser. No. 706,017

9 Claims. (Cl. 28—76)

This invention relates to cut pile carpeting whether tufted, woven, or knitted, and if woven, whether produced as Axminster, Brussels, broadloom, velvet or other type. More particularly, the invention deals with the tufts of cut pile carpeting, with a new plied composite yarn strand for forming the tufts and with a method of making the carpeting.

It is a primary object of the invention to provide a cut pile carpet having tufts formed of composite yarn strands, one of which strands of the composite has superior wear resistant properties and another yarn of the composite being of a material which is highly crimped and which lies close to the backing fabric so as to lend support to the wear resistant yarn and to impart an improved body and feel to the carpet.

Another object of the invention is to provide a composite yarn strand formed of at least two different types of yarn and which is suitable for use for forming the tufts of cut pile carpeting.

Still another object of the invention is to provide a cut pile carpet having tufts formed of plied strands of wool and a special type of water crimpable regenerated cellulose.

A further object of the invention is to provide a method of making carpeting having tufts comprising a wear resistant yarn which extends a substantial distance upwardly from the backing fabric to provide a wear resistant surface and a cellulose acetate or regenerated cellulose yarn tightly crimped about the wear resistant yarn and lying close to the backing fabric.

Other and further objects, features, and advantages of the invention will become apparent as a description of a preferred embodiment thereof proceeds.

Referring now to the drawing:

Figure 1 is a diagrammatic side elevational view of a carpet made in accordance with the present invention;

Figure 2 is an enlarged view showing one of the tufts secured to the backing fabric of the carpet, before the carpet has been immersed in water;

Figure 3 is a view similar to Figure 2 but shows the effect of immersing the carpet in water;

Figure 4 is a diagrammatic view of a composite yarn strand made in accordance with the invention; and

Figure 5 is a diagrammatic representation of a segment of the new yarn showing the effect of immersing the yarn in a liquid medium.

In accordance with the present invention a yarn strand 10 is twisted or plied together with a yarn strand 11 as shown in Figure 4. The strand 10 may be formed of wool fibers or may be formed of continuous filaments of nylon or other material having exceptional wear resistant and soil resistant properties, wool ordinarily being preferred. The strand 11 is formed of continuous filaments of a special type of rayon which has the characteristic of spontaneously assuming a permanent crimp when subjected to an aqueous liquid such as water. Inasmuch as the method of making this special type of rayon does not form a part of the present invention, the

same need not be described in this specification but reference may be had to the patents to Merion et al., No. 2,517,694, Kulp et al., No. 2,572,936, or Nicoll, No. 2,515,834 for a description of the methods of making a suitable yarn. As described in the first two patents the filaments are formed of regenerated cellulose and have a non-uniformity of structure cross-sectionally thereof which causes such filaments to assume a permanent tight crimp very rapidly when immersed in water while the 10 yarn is free of tension. When the yarn is made as described in said first two mentioned patents no swelling of the yarn takes place when it is immersed in water but only the above referred to crimping action. The yarn described in the Nicoll patent not only crimps when immersed in water but also swells and for this reason may not be as satisfactory for all purposes as the yarns described in the Merion and Kulp patents.

Since, as previously mentioned, the invention is equally applicable to all types of cut pile carpeting, the drawing 20 merely indicates generally a tufted carpet having a backing fabric 12 to which the tufts are sewn. The tufts are formed of composite yarn strands as shown in Figure 4, each of the individual strands of the composite strand being of substantially the same overall length. It is to be 25 particularly noted that the composite yarn strand is not a blend of different fibers but comprises two distinct yarn strands. There may be more than two strands and the strand 10 may itself be a blend but in accordance with the present invention the strand 11 must be formed of 30 continuous filaments of a liquid crimpable yarn.

After all of the tufts have been inserted, the carpeting is immersed in cold water, or other aqueous liquid depending upon the particular nature of the yarn 11, whereupon the strand 11 of the composite strands of the 35 tufts spontaneously crimps tightly and permanently about the non-crimping strand 10, the free ends of the strands 11 moving down close to the backing fabric during the crimping process. This leaves the strands 10 extending upwardly from the backing fabric considerably further 40 than the strands 11 so as to provide a surface consisting of a single type of yarn. The superior wearing qualities of wool, and the fact that wool does not soil easily and when soiled is easy to clean, recommend this yarn for carpeting use. However, wool is quite expensive and the 45 present invention by combining the wool with rayon in the manner above described provides a carpeting having many of the qualities of an all wool carpet at considerably less expense than all wool carpeting. While wool is superior in many respects, the invention contemplates that the strand 10 may be some other yarn having good wear resistant qualities.

The special rayon of the yarn 11, by crimping about the yarn 10, as shown, gives support to the fibers of the strand 10 and causes the tufts to stand upright and resist 50 matting. The tight crimp or coil of the strand 11 also gives increased body to the carpet and gives the carpet a more springy and comfortable feel. It is well known that rayon has not been as widely used in carpeting as might otherwise have been the case because its wearing 55 properties are such that it is not particularly suited for the type of wear ordinarily imposed upon carpets. However, with a carpet constructed in accordance with the present invention, it will be observed that the rayon is not subjected to any abrading action because the wear 60 resistant yarn 10 such as wool, by extending higher than the rayon, takes all the wear.

In addition to the above advantages, it has been found that some very interesting color effects may be obtained in a carpet of this type since the wear resistant yarn will not have an affinity for the same types of dyes as will the crimped yarn. Thus, for example, the crimped yarn may be dyed a color contrasting with the color of the surface

forming yarn and the color of the crimped yarn will be visible when and only when the surface yarn is brushed down.

Having thus described the invention, what is claimed is:

1. For forming tufts in cut pile carpeting, a composite yarn strand comprising a first strand of a yarn having the characteristic of assuming a permanent crimp when a liquid is applied thereto, a second strand of a yarn not having this crimping characteristic, and said strands being plied together.

2. For forming tufts in a cut pile fabric, a composite yarn strand comprising a strand of wool fibers, a strand formed of a material which will crimp when a liquid is applied thereto, and said strands being plied together.

3. For forming tufts in a cut pile fabric, a composite yarn strand comprising a strand of wool fibers and a strand of substantially straight continuous filaments, said filaments being formed of regenerated cellulose and having a non-uniformity of structure cross-sectionally thereof whereby said filaments have the characteristic of spontaneously crimping when subjected to an aqueous liquid, and said strands being plied together.

4. A cut pile carpet comprising a backing fabric, tufts secured in said backing fabric, said tufts comprising plied strands of a wear resistant yarn and a highly crimped yarn, said wear resistant yarn extending upwardly from said backing fabric further than said highly crimped yarn and said crimped yarn helping to hold said wear resistant yarn upright.

5. A cut pile carpet comprising a backing fabric, tufts secured in said backing fabric, said tufts comprising plied strands of wool and crimped rayon, said wool strands extending upwardly from said backing fabric further than said crimped rayon so as to provide an all wool wearing surface.

6. A cut pile fabric comprising a backing fabric, tufts secured in said backing fabric, each of said tufts comprising a plied strand of wool yarn and crimped rayon yarn, said yarn strands having substantially the same over-all length, said wool strand extending upwardly from said backing fabric further than said crimped rayon strand to provide a wear resistant surface, and said crimped

rayon strand being tightly coiled about the wool strand close to said backing fabric to provide a resilient feel to the carpet.

7. A cut pile carpet comprising a backing fabric, tufts secured in said backing fabric, said tufts comprising plied strands of a wear resistant yarn and a highly crimped yarn, said wear resistant yarn extending upwardly from said backing fabric further than said highly crimped yarn, said crimped yarn helping to hold said wear resistant yarn upright, and said yarns having affinity for different types of dyes whereby a two-color effect may be obtained by subjecting the carpet to different types of dyes.

8. An intermediate article in the manufacture of cut pile carpeting comprising a backing fabric, tufts secured in said backing fabric, said tufts being formed of composite strands comprising a strand of wool fibers and a strand of substantially straight filaments, said wool strands and said filament strands being plied together, said filaments being formed of regenerated cellulose and having a non-uniformity of structure cross-sectionally thereof whereby said filaments have the characteristic of spontaneously crimping when immersed in water.

9. A method of manufacturing cut pile carpeting having tufts formed of composite yarn strands one of the strands of which extends outwardly a substantial distance from the backing fabric of the carpeting and another strand of which is tightly coiled about the first and lies close to the backing fabric, comprising forming tufts of substantially co-extensive plied strands of a wear resistant yarn and a yarn having the characteristic of permanently crimping when treated with an aqueous liquid, and subjecting the carpeting to an aqueous liquid to thus cause the yarn having the characteristic of crimping to crimp.
